US00D878360S

(12) **United States Design Patent** (10) **Patent No.:** **US D878,360 S**
Sun et al. (45) **Date of Patent:** **** Mar. 17, 2020**

(54) **DATA PROCESSING DEVICE FOR AN INDUSTRIAL COMPUTER**

7/00; H05H 7/20; G11B 33/126; G11B 33/128; G11B 33/08; G11B 33/02

See application file for complete search history.

(71) **Applicant:** **SIEMENS AKTIENGESELLSCHAFT**, München (DE)
